Application December 30, 1937, Serial No. 182,452

5 Claims.

(Cl. 38—41)

The present invention relates to garment or laundry presses of the multicylinder type and has for an object, the provision of a simple mechanical construction by which the press may be closed preliminarily under light pressure and a heavy pressure thereafter developed to complete the pressing operation.

It is a further object to provide a mechanism which will be economical in the use of compressed air.

It is a further object of the invention to provide a mechanism which will during usage automatically compensate for compression of the buck pad and variation of thickness of garments being pressed.

It is a further object of the invention to provide a multicylinder machine in which one of the cylinders acts alternatively as motor cylinder and as a buffer cylinder, whereby the opening of the press is timed and cushioned.

It is a further object of the invention to provide a system of controls whereby it is impossible for the operator of the press to become injured while operating the press.

These and other objects of the invention will become apparent in the description.

In the description hereinafter given reference is had to the accompanying drawings in which like characters represent corresponding parts in all views.

Figure 1 is a side elevation of the pressing machine showing the parts disposed when the press is in open position.

Figure 2 is also a side elevation of the press, partly in section and with some of the elements removed, showing the mechanisms disposed as they are when the press is in partly closed, and closed positions.

Figure 3 is a fragmentary front view of the press, showing the controls.

Figure 4 is a diagrammatical view showing certain of the operating elements of the press, together with the control valves and the connecting lines as they are positioned when the press is in the open position.

Figure 5 is also a diagrammatical view showing certain elements of the press, control valves and connecting lines as they are positioned when the press is in closed position.

Figure 6 is a kinematic diagram showing the various pressing elements in a plurality of positions between the open position and the several closed positions.

The pressing machine of the present invention comprises a main frame which may, if desired,

be fabricated from structural shapes. It comprises bed frame 1 upon which are mounted columns 2 and 3, and top frame 4. Mounted upon the top frame 4 adjacent column 3 is a pedestal 5 which serves to carry stationary pressing buck 6 which is covered with a conventional buck pad 7. This pad may be of any desired construction such as a cotton-filled, cloth-covered pad, or a pad containing a large number of small springs, or other resilient elements. While the details of the pad construction form no part of the present invention it should be borne in mind that buck pads as presently used frequently consist of material which is loose and thick when fresh, but which becomes matted and takes a permanent set as it is used. This results in a gradually receding surface 8 upon which the cooperating movable pressing member 9 seats. The movable pressing element 9 is heated in any desired manner, such as by steam under pressure, or electrically, and is carried by a pressing arm 10 which is pivoted at point 11 at the upper end of column 2.

The operating mechanism of the press includes two pneumatic motors 12 and 13. Motor 12 consists of a cylindrical shell 14 in which piston 15 and piston rod 16 move when air under pressure is admitted thereto. The lower end of motor 12 is pivoted to column 2 at point 17 and the piston rod is connected by means of clevis 16a at its upper end to pivot point 18 on presser arm 10 (as shown in Figs. 1 and 2). It will be observed that in this construction piston rod 16 acts directly upon the movable presser arm 10 to change its position from the open position shown in Figure 1 to the position shown in the full lines of Figure 2.

The second motor 13 is preferably of larger diameter than the first motor 12 and is for the purpose of applying heavy pressure to the buck after the head 9 has been brought into engagement with the buck through the preliminary action of motor 12. Motor 13 consists of a cylindrical member 19 which is held between cylinder heads 20 and 21 by means of through bolts 22. The cylinder head 20 is constructed so that it can be pivoted at point 23 upon bracket 24 which is in turn mounted upon channel 25 and column 3. Piston rod 26 carries piston 27 in cylinder 19 and is provided at its outer end with a bifurcated member 28 which is adjustably mounted upon the threaded portion 29 of the rod. The bifurcated member 28 is shaped so as to straddle an upright bracket 30 which is shaped so as to form a cam trackway having arcuate

sections 30 and 31. A roller 32 is mounted upon journal pin 33 in the end of bifurcated member 27 and is of a size such that it neatly fits between the opposed surfaces of the trackway 30-31. It will be noted also that the ends of bifurcated member 27 are widened so as to slide against the side faces 34 of the trackway.

Pin 33 extends beyond the outer surfaces of bifurcated member 27 and serves to join that member with a similar bifurcated member 35. Clevis 37 is adjustably attached to bifurcated member 35 by means of screw 36 so that the three members form a solid inextensible link. The upper end 37 is pivoted to arm 10 at the same point 18 which serves as a pivot point for the piston clevis 16a.

The bracket 29, in which cam track 30-31 is formed, is mounted in fixed relationship with respect to the lower horizontal member 1 of the frame. The details of the cam track construction are illustrated in Figure 6 which shows the operating linkages in six illustrative positions *a*, *b*, *c*, *d*, *e* and *f*. The lower portion 30 of the cam track is an arc of a circle which has as its center the pivot pin 38 by which the base 20 of cylinder 19 is affixed to frame 3. The upper portion 31 of the cam track is also an arc of a circle but in this case the center is point O which is below and toward the pivot point 11 from a reference point *d'* which represents one position of pivot 18 as the presser head 9 approaches the free position D of the buck 8. It will be observed that the radius OA of the arc AC is somewhat less than the length of link 35. This fact and the chosen position of point O combine to give a rising characteristic to the arc AC with the result that as roller 32 is forced outwardly along the arc AC the link 35 will be given an upward thrust. In the diagram Figure 6 the arc BC is a portion of a circle of radius equal to the length of link 35 (taken to the outer surface of roller 32) about position *d'* as a center, and as such represents the curve along which roller 32 might move freely without giving link 35 any upward component of movement. The solid angle ϕ between the intersecting arcs AC and BC thus represents a curved wedge surface by which the outward movement of extensible link 25-27 is given a small upward component at greatly increased force so that the presser head 9 is moved home upon buck pad 7. It will be noted that the two arcuate sections 30 and 31 are smoothly joined by a third arc 39 which is preferably of relatively short radius.

It is to be understood that the location of point O is not critical and may be varied within limits. In some instances it is desirable to decrease slightly the radius of the outermost section of the arc 3, as for instance the section between position *e* and *f* of roller 32.

The press is provided with a pair of springs 40 which are pivotally attached as at point 98, one at each side of and at the upper end of presser arm 10, and at their lower ends to brackets 41 on the base. The press is also provided with a pair of springs 42 which are adjustably attached at their upper ends to boss 43 on the bifurcated member 35, and at their lower ends are attached to brackets 44 on the base of the machine. Only the spring in the near side of the machine is visible in Figures 1 and 2. Each draw rod 43a telescopes into its spring 20 as to bring it into action a short distance before the roller 32 reaches curved section 39 of the cam track. This retards the rapid downward motion 75

of the presser head and prevents any shock of the head against the padded buck. Springs 42 also have the added function of assisting the rapid opening of the press by freeing the air out of cylinder 13. All of the springs are adjusted so as to open the press and to maintain it in the normal position shown in Figure 1.

The controls of the press consist of a plurality of manually operable buttons 45, 46 and 47 which are slidably mounted in openings 48 in the table panel 49 of the press. The stems 50 are pivoted to rocker arms 51 as shown in Figure 1 which serve to communicate the downward movement of an operated button to the stems 52, 53, and 54 of the control valves.

Button 45 actuates the release valve 55 of the press, whereas buttons 46 and 47, respectively, actuate the right-hand control valve 56 and left-hand control valve 70. The release valve 55, and the right-hand control valve 56 are embodied in one casing which has an air supply chamber 57 and a plurality of valve ports 58 and 59. Valve port 58 communicates with antrum chamber 60 which in turn is connected to release cylinder 100 by connecting line 61. Valve port 59 communicates with antrum 62 which in turn is connected to supply section 63 of the left-hand control valve 70 by way of line 64. The release valve casing is provided with a poppet-type valve having head portion 65 which serves to close port 58 when the valve is moved under the influence of spring 66. The right-hand control valve 56 is provided with a similar poppet valve. It will be noted that the junction between the small and large portions of stem 53 of the valve serve as a valve to open and close port 67, the purpose of which will be explained subsequently.

The left-hand control valve 70 is similar to the right-hand control valve and consists of a supply chamber 63, valve port 68, and antrum 69 which is connected with operating cylinder 12 by means of line 117. The casing of the left-hand valve 70 is provided with a port 71 which is closed when the valve port 68 is opened, and is open when the valve port 68 is closed, due to the construction of the valve stem. This port is connected through metering orifice 72 which has an adjustment screw 73 by which the flow of air through the orifice can be regulated.

The press is also provided with an automatic valve 75 which is mounted upon column 2. This valve consists of a casing having four sections 76, 77, 78 and 79. Section 76 communicates with section 77 by means of valve port 80 which may be closed by the head 81 of valve 82. Section 77 is at all times in communication with section 79 by means of passageway 83. Section 78 communicates with section 78 by means of valve port 84 which may be closed by the head 85 on valve 86. Valves 82 and 86 are provided with springs 87 and 88 which normally tend to seat the valves against their valve ports. The two valves 82 and 86 are operated by rocker arm 89 which is provided with adjustment screws 89 and 90 which serve to operate valves 82 and 86, respectively. The rocker arm 89 is also provided with an arm 91 which extends to the right, as shown in Figure 2, and is normally biased upwardly by spring 92. The upper end of the rocker arm 89 is curved to the left, as shown in the drawings, and is provided with a roller 93 which is positioned so as to be engaged by cam surface 94 on cam rod 95.

The cam rod 95 consists of a slotted lower sec-

tion 96, a cam surface 94, and an upper link 97 which is pivotally attached to presser arm 10 at point 98. The cam rod normally hangs freely but is drawn to the right by means of the release mechanism generally designated 100. This mechanism is shown in detail in Figure 5 and consists of a cylinder 101 in which piston 102 and piston rod 103 operate. The rod 103 carries a clevis 104 at its outer end which carries roller 105 in the slot in the lower section 96 of cam arm 95. Clevis 104 is provided with a cross-bar 106 which is normally biased to the right by means of springs 107, as shown in Figures 1 and 2. A spring 108 is provided within cylinder 101 and serves to cushion piston 102 when it is moved to the left (see Figure 5).

Operation

The press is normally in the position shown in Figure 1, at which time the release valve 55, the right-hand control valve 56, the left-hand control valve 70, and valve 82 of the automatic control valve 75 are in seating engagement against their respective valve ports. In order to operate the press, buttons 46 and 47 are depressed. This serves to open the right-hand control valve 56 and the left-hand control valve 70, thereby providing a free passage for the air from supply line 110 through line 111 to air supply section 57 of release valve and right-hand control valve. Air flows from the air supply section 57 through the open port 59 to antrum chamber 62 of the right-hand control valve and thence by line 64 to the supply section 63 of the left-hand control valve 70. Since valve port 68 is also open, air flows to antrum 69 and thence by line 117 to cylinder 14 of motor 12 where it forces piston 15 and piston rod 16 upwardly to the position shown in full lines in Figure 2. During this time springs 107 of the release mechanism hold the roller 105 in the position shown in Figure 2, with the result that as the press closes, cam section 94 forces roller 93 to the right, as shown in Figures 2 and 5, so as to close valve port 84 and open valve port 80 of the automatic valve 75. The valves are then in the condition shown in the full lines in Figure 5 and air accordingly flows from supply line 110 through 112 to section 76 of the automatic valve 75 and thence through open port 80 to section 77 through passage 83 to section 79. It will be noted that valve 85 covers valve port 84 and thus prevents the passage of air to section 78. Air under pressure is accordingly driven through line 113 to heavy pressure motor 13 and the piston 26 and piston rod 25 are extended and a heavy pressure produced between the movable pressing head 9 and the pad 7 of the buck 6.

The stopping position of the roller 32 along arcuate portion 31 of the cam trackway is determined by the air pressure in the cylinder 19, the force exerted by springs 40 and 42, and the resisting pressure of the buck pad 7. When the pad is fresh and thick, or when a heavy garment is in the press, the roller will cease movement at the position *d* of Figure 7. In this position the presser head is in contact with the pad at level D. As the pad 7 is compressed during use, the surface is gradually lowered from D to position E and then to the limiting position F. Thus the limiting positions of roller 32 will gradually shift from position *d* of Figure 7, which is the position when the pad is fresh, through to position *e*, and then to position *f*, which is the position when the pad has been fully compressed in

use. Adjustment of the press to accommodate for the compression of the pad is thereby rendered unnecessary.

This automatic adjustment feature also compensates for variations in the thickness of garments being pressed. It should be noted that adjusting screws on piston rod 25 and on link 35-36 need not be varied after the machine is assembled and balanced. The upward force exerted by link 35-36 increases slightly as the limiting position of roller 32 moves to the left, as shown in Figure 2, due to the fact that link 35-36 becomes nearer the right angle position with respect to presser arm 10, but this increase is counteracted by the increased tension in springs 40 and 42. This results in a substantially constant pressure being exerted upon the pad whether it is new and thick, or compressed as after severe usage.

It will be noted that piston 26 is not moved in cylinder 19 during the time the press is being opened or closed under the influence of motor 12 because section 30 of the cam track is the circumference of a circle, the center of which is pivot point 38. Thus as the pressing elements close upon each other, the roller 32, bifurcated member 27, piston rod 25, and cylinder 13 simply oscillate upwardly without being extended, until the roller reaches the circular section 39 of the trackway.

The cam track 94 is adjusted with respect to link 97 so that the automatic valve is operated as the roller 32 reaches section 39 of bracket 29, with the result that the heavy pressure cylinder 19 is completely inactive during the initial press closing operation and is then brought into activity only as the press approaches the closed position and pressure is ready to be generated between the opposed pressing elements 7 and 9.

As the press is moved under the influence of heavy pressure motor 13, piston 15 in cylinder 14 uncovers port 114, thereby permitting air which is under pressure in the cylinder, to escape. In operation the operator removes pressure from buttons 46 and 47 at about the time the heavy pressure motor 13 takes over the operation of the press. The communicating passage from air supply 110 through chamber 56 of right-hand valve 55, valve port 59, chamber 62, line 64, chamber 63 of left-hand valve 70, valve port 68, chamber 69 and line 117 to cylinder 14 is interrupted by the closure of valve ports 59 and 68. The fluid under pressure in cylinder 14 will continue to exhaust from port 114 until atmospheric pressure is established. The importance of this will be explained subsequently.

The press will remain closed under the influence of heavy pressure motor 13 until the release valve is operated by pressure upon button 45. When this occurs valve stem 52 is depressed and air is admitted from air supply chamber 57 through valve port 58 to antrum chamber 60 and thence by way of line 61 to the cylinder 101 of release mechanism 100 where it forces piston 102, piston rod 103, and roller 105 to the left from the heavy line position to the dotted line position, as shown in Figure 5. The movement of roller 105 causes cam arm 95 to oscillate to the left and rocker arm 88 is rotated in a counterclockwise direction due to the tension of spring 92. Valve 82 is thereby closed and valve 86 opened. The closure of valve 82 interrupts the air supply from line 110 to heavy pressure motor 13, and at the same time opens valve 86 and thus permits the free passage of the air which is under pressure in

cylinder 19 of motor 13, through line 113 to chamber 79 and thence through valve port 84 to chamber 78 and by way of line 116 to muffler 118. The press immediately begins to open under the influence of springs 40 and 42, and the pistons of both cylinders are forced toward their respective cylinder heads. As the piston in motor 12 passes port 114 air is entrained and forced back through line 117 to antrum chamber 69. The left-hand valve is closed at this time with the result that the air passes from chamber 68 through side port 71 and to atmosphere through orifice 72. Screw 13 is adjusted so that the opening of the press will be cushioned. By restricting orifice 72 the time of opening of the press can be regulated as desired. Since air is the cushioning medium a substantially constant cushioning and timing effect will result. This is obtained because the viscosity of air is substantially constant (as compared with fluids such as oil) because the air is always entrained at atmospheric pressure and because the percentage variation in the absolute temperature of the air throughout the range of operation temperatures, is very small.

In the event left-hand valve 54 has been held open, the air from cylinder 14 will not be permitted to escape at port 71 and will be forced through chamber 69, valve port 68, chamber 63, and thence through line 64 to antrum chamber 62. The right-hand valve 53 is assumed to be in the unoperated position and valve port 69 will be closed and side port 67 open, thereby permitting the escape of air by means of the side port.

The invention herein described is illustrated in its preferred embodiments but changes and modifications may be made without departing from the scope of the invention as set forth in the appended claims.

What I claim is:

1. A garment or laundry press comprising a frame, a presser arm pivoted intermediate its ends on said frame, a stationary pressing element mounted on the frame, a movable pressing element mounted on said presser arm for cooperating engagement with said stationary pressing element, a first longitudinally extensible fluid motor coupled between the frame and presser arm for actuating the latter, a second longitudinally extensible motor, pivot means for connecting one end of said second motor to the frame, an inextensible link having one of its ends pivotally connected to the presser arm and the other of its ends pivotally connected to the second motor, and cam guide means for the pivotal connection between the inextensible link and the second motor.

2. In a garment or laundry press, a frame for said press; a presser arm pivoted intermediate its ends on said frame; a stationary pressing element; a movable pressing element mounted on one end of said arm for a cooperating engagement with said stationary pressing element; a first fluid motor capable of extending longitudinally when actuated, coupled between said frame and the other end of said presser arm for moving the movable pressing element into engagement with the stationary pressing element; an actuating mechanism comprising an inextensible link and an extensible link pivotally connected together, said extensible link being a sec-

ond fluid motor, said actuating mechanism being connected between said frame and said movable presser arm, and a cam guide for the pivotal connection between said links, whereby heavy pressure may be applied by the movable element after it has been moved into preliminary engagement with said stationary element; a manual operable valve means for applying fluid pressure to said first fluid motor to preliminarily close the press, and mechanically operated valve and means operating said valve when said press has reached a predetermined closed position, to apply fluid pressure directly to said second motor; means to exhaust all but a fixed volume of fluid from said first motor when the press is moved to its full operative position by the second fluid motor and to entrain said fluid as the press opens, and means to regulate the escape of the entrained air so as to time the opening of the press.

3. In a garment or laundry press, a frame; a presser arm pivoted intermediate its ends for oscillation with respect to said frame; a pair of cooperating pressing elements, one mounted on the frame and another on the arm; a link pivoted to said arm at a point removed from the pivot point of the arm on the frame, and a longitudinally extensible fluid motor, pivoted at one end to said frame and pivotally connected at the other end to said link; a cam surface for guiding the pivotal junction point of said link and said longitudinally extensible motor, comprising a segment of a circumference smoothly joined to a substantially arcuate wedge oriented so that motion of the junction point along said arcuate wedge moves the press toward closed position; and motor means for moving the pivotal junction of said longitudinally extensible motor and said link along said cam surface.

4. A pressing machine comprising a frame; a presser arm pivotally mounted on said frame, a cylinder and piston therefor, a pivot for mounting the cylinder on the frame and a link directly connected between the presser arm and piston rod whereby the cylinder and piston rod will be moved about the cylinder pivot as a center when the presser arm is moved from open press position toward closed press position, and a cam guide including an arcuate segment oriented around the cylinder pivot point as a center for restraining outward movement of the piston rod throughout a portion of said press closing movement, and a wedging segment oriented substantially radially with respect to the cylinder pivot.

5. A pressing machine comprising a frame, a presser arm pivotally mounted on said frame, a cylinder and piston therefor, a pivot for mounting the cylinder on the frame and a link directly connected between the presser arm and piston rod whereby the cylinder and piston rod will be moved about the cylinder pivot as a center when the presser arm is moved from open press position toward closed press position, and a cam guide including an arcuate segment oriented around the cylinder pivot point as a center for restraining outward movement of the piston rod throughout a portion of said press closing movement, and a wedge segment formed to present a progressively increasing deviation towards the presser arm from a radius through the cylinder pivot.

JOHN F. RAYNOLDS.
